UNITED STATES PATENT OFFICE.

EDGAR C. PLANT, OF MOMENCE, ILLINOIS, ASSIGNOR TO ALEXANDER A. FORDON, OF BUFFALO, NEW YORK.

DESIGN FOR AN ALTO-RILIEVO.

SPECIFICATION forming part of Design No. 22,145, dated January 24, 1893.

Application filed November 5, 1892. Serial No. 451,115. Term of patent 3½ years.

To all whom it may concern:

Be it known that I, EDGAR C. PLANT, a citizen of the United States, residing at Momence, in the county of Kankakee and State of Illinois, have invented a certain new and useful Design for an Alto-Rilievo, of which the following is a specification, reference being had to the accompanying drawing, in which the figure is a front view.

10 The leading feature of my design consists in an alto-rilievo bust of Christopher Columbus, surrounded by a horse-shoe *a*, the upper portion of the bust being below the arch of the horse-shoe, which is also in relief. At 15 suitable points in the shoe nails *b* are shown, some of which are shown as being partly

drawn out, while others are closely fitted in the shoe. At the upper portion of the shoe is a space *c* suitable for inscriptions, and near the ends of the shoe are other spaces, *d*, *d* 20 also suitable for inscriptions. The general effect produced is that of the bottom of a horse's hoof, carrying the shoe, with a bust of Columbus in relief therein.

I claim,—

25 The design for an alto-rilievo substantially as herein shown and described.

EDGAR C. PLANT.
